OIL PRESS

William Hise, Englewood, and Arthur M. Dietrich,
South Orange, N. J., assignors to The Baker
Castor Oil Company, Jersey City, N. J., a cor-
poration of New Jersey

Application May 10, 1946, Serial No. 668,652

12 Claims. (Cl. 100—215)

1

This invention relates to a press by means of which oil can be pressed from seeds with very little attention on the part of the operator. The invention is particularly useful for pressing oil from castor beans.

The invention may be understood from the description in connection with the accompanying drawings in which—

Fig. 1 is a side view partly in section showing the press;

Fig. 2 is a longitudinal section through a valve;

Fig. 3 is a plan view of the feed part of the press including the piston part of a jack;

Fig. 4 is a view looking at the lower end of Fig. 2;

Fig. 5 is a diagram showing the power distribution line of the device;

Fig. 6 is a section on a large scale showing one of the operating members for the press;

Fig. 7 is a bottom plan view of a portion of Fig. 6, this portion being the principal stationary member of the unit controlling the operation of the press;

Fig. 8 is a bottom plan view similar to Fig. 7 showing in solid lines the lower movable member of the control unit and showing in dotted lines portions of said principal stationary member and of the upper movable member;

Fig. 9 is a plan view of an intake plate for the device; and

Fig. 10 is a plan view of an exhaust plate for the device.

In the drawings, reference character 1 indicates an inlet pipe for castor beans and this pipe extends into a conduit 2 that is provided with a ring having an arm 3 attached thereto. A jack 4 is provided. This jack has a piston rod 5 that is connected to a slot 4' in the arm 3. An inlet 6 and an outlet 7 are provided for fluid that is used for operating the piston rod 5. A support 8 (Fig. 1) is provided for the jack 4 and other parts are mounted on this support as shown. Standards 9 are provided for the support 8 and a base 10 is provided for the standards 9.

A cylindrical member 12 extends through an opening in the support 8 and is supported on the support 8 by flange 13. Arcuate openings 14 are provided through the lower enlarged end or press head 15 of the cylindrical member 12. Side outlets 16 (Fig. 2) are provided along opposite sides of the lower end of the conduit 2. Diametrically spaced extensions 17 are left at the lower end of this conduit. A cross-piece 18 extends across the lower end of the conduit 2 and has a central opening through which a bolt

2

19 extends. The threaded conically-shaped portion 19' of the bolt 19 carries a thick disk 20 that is provided with arcuate openings 14' that can be brought into alignment with openings 14.

5 A vertically movable cylinder or container 21, in which the enlarged end 15 of the cylindrical member 12 fits, is operated by hydraulic jacks 22 and pistons 22' on opposite sides of the container 21. A horizontally movable cylindrical container or pot 25 is provided with perforations 26 through the side wall thereof. This pot rests upon a support 27 that can be moved up and down. A circular groove 28 is provided along the top side of the support 27 outside of the pot 25. An outlet pipe 29 extends from the groove 28 for the oil.

10 Fig. 20 is a section on a large scale showing one of the operating members for the press; 20 A hydraulic jack 30 (Fig. 1) is anchored in position. It is provided with a push rod 31 and a pivot plate 32 for pushing the container 25 out after oil has been pressed out of the beans. Hydraulic jacks 22 are provided on opposite sides for raising the cylinder 21, when desired.

15 A support 34 is provided upon which the container 25 is movable by jack 30. An outlet 35 is provided for the pulp. A ram or movable member 37 is provided with arms 38 for removing the residual pulp in container 25 after the oil has been pressed out of the beans. A jack 39 is provided with an inlet 40 and an outlet 41 for operating the ram 37.

25 Fig. 35 is a section on a large scale showing one of the operating members for the press; 35 A valve casing 44 (Fig. 6) is provided with a series of inlets and outlets for compressed air. The inlet is shown at 45 and the outlet at 46. Other similar inlets and outlets are provided as shown by Figs. 7 and 8, somewhat diagrammatically. A thick disk 47 is clamped by bolts 48 in the casing 44. An inlet plate 50 and an outlet plate 51 are located in the casing 44. These plates are revolvable and driven by a shaft 40 52 which carries cross-pins 52a and 52b to drive these plates. An air conduit 53 extends inwardly from the edge of the disk 47. An opening 54 is provided through the disk 47 at right angles to the conduit 53 at the inner end thereof. This opening 54 terminates in a smaller opening 54'. An annular groove 56 is provided along the lower side of the disk 47 starting at the lower end of the opening 54 and terminates short of a circle. An arcuate groove 58 is provided in the lower side of the disk 47 outside of and overlapping the ends of the groove 56. A wheel 59 (Fig. 5) is driven by a motor, not shown. This wheel is attached to the shaft 52 so that the intake plate 50 and exhaust plate 55 51 are driven in synchronism. The plate 50 is

provided with holes 50a, 50b and 50c (Fig. 9) extending therethrough. The disk 51 is provided with holes 51a to 51h (Fig. 10) therethrough.

The flanged disk 65 (Fig. 6) is fixedly attached to the shaft 52 and revolves with it. The hub 66 on disk 51 is driven by the shaft 52. A cross-pin 52b extends through this hub and shaft. A compression spring 64 keeps the disks 50 and 51 in sliding contact with the thick disk 47. The contacting surfaces of the disks 47, 50 and 51 are smooth and are spring-pressed together by the spring 64, but the disks 50 and 51 can be revolved by the shaft 52.

The operation is as follows:

With the parts in the position shown in Fig. 1 and shaft 52 being revolved in any convenient way, air under pressure is applied to the jacks 22 and 22a (Figs. 1 and 5) through line 23, thus holding the cylinder 21 a short distance above the pot 25. This occurs due to the fact that compressed air is supplied through inlet 45 (Fig. 6) and passes through hole 50b (Fig. 9) in plate 50 into groove 58 in the fixed disk 47 (Figs. 6 and 7) and out of the conduit 53b and through line 23 into jacks 22, 22a, thus holding the cylinder 21 in its upper position.

As soon as the plate 50 has been turned to the position where groove 58 (Fig. 7) does not communicate with inlet 45 through hole 50b, the air pressure is cut off and communication is established by the conduit 53b, openings 54 and 54' in the disk 47 and outlet hole 51h (Fig. 10) in plate 51 and thence through outlet 46, thereby releasing pressure in the jacks 22 and 22a and permitting the cylinder 21 to descend and rest upon the pot 25.

The next step is opening of the valve 14 (Fig. 2) by means of jack 4 (Fig. 5) to feed beans to the pot 25. This opening of the valve occurs when the hole 50c in plate 50 reaches the hole 62 (Fig. 7) in plate 47, and continues until this hole 50c reaches the hole 63 in the stationary plate 47. At this stage pot 25 has been filled and cylinder 21 is partially filled and the piston 5 (Figs. 2, 3 and 5) is thereby moved to close the valve 14 because air enters jack 4 through line 6. The hydraulic jack 33 is then operated in the known way by opening a valve by hand or power to raise the support 27, cylinder 21 and pot 25, thus causing the oil to be pressed out of the beans and flow into groove 28 and through outlet pipe 29 to storage. The jack 33 is then lowered to the position shown in Fig. 1 by opening another valve by hand or power.

After the pots reach this lowered position, the upper cylinder 21 is raised by fluid such as air under pressure entering inlet 45 (Fig. 6) and passing through hole 50b (Fig. 9) in plate 50 which is then aligned with groove 58 in the fixed plate 47 (Fig. 7) and thence into jacks 22, 22a (Fig. 5), thus moving cylinder 21 to its upper position. The jack 30 is then operated to push the pot 25 out. This is done by the hole 50c (Fig. 9) reaching the outlet 59 (Fig. 8), thus admitting air under pressure to the right-hand end of jack 30 (Fig. 5).

The ram 37 is then lowered when the hole 50c (Fig. 9) reaches the outlet 59 (Fig. 8), compressed air being thereby admitted through pipe 40 (Fig. 5) into the upper end of the cylinder 39. This lowering of the ram forces the pulp from pot 25. The ram 37 is then raised when the hole 50a (Fig. 9) reaches the outlet 54 (Fig. 7), compressed air being thereby admitted through pipe 41. During the remainder of the operating cycle, the

ram 37 is maintained in the raised position, since the hole 50a in plate 50 mates all this time with groove 56 in the thick stationary disk 47, thus permitting air under pressure to pass out through the corresponding conduit 53 (Fig. 7) in disc 47, and into pipe 41 and then into the lower end of the jack 39 (Fig. 5).

When the hole 50c in plate 50 reaches hole 61 (Fig. 7) in disc 47, the jack 30 is then operated to return the pot 25 to pressing position. The cylinder 21 then descends and rests upon the pot 25, the air pressure in the jacks 22 and 22a being released via air conduit 53, opening 54' in the disc 47, outlet hole 51h (Fig. 10) in plate 51, and outlet 46. When the hole 50c reaches hole 62 compressed air enters the jack 4 (Fig. 5) through the pipe 7, thus opening the gate 14, and thereby permitting seed to flow into the pot 25 and cylinder 21. When the hole 50c reaches hole 63, compressed air enters the jack 4 through the pipe 6 and closes the gate 14, thereby cutting off the flow of seed into the pot 25 and cylinder 21, which are filled with seed at this stage.

So long as the hole 50a mates with the groove 56 air goes through the hole 50a and groove 56 to the port hole 53 and then to the lower end of the jack 39 (Fig. 5) to keep the ram 37 in its upper position. In order to raise the cylinder 21, air is caused to enter the hole 50b in the disk 50 and the groove 58, then out through another port hole 53b in the thick disk 47. The cylinder 21 is then in its upper position.

When the hole 50c in disk 50 reaches the hole 59 in the stationary disk 47, air forces the piston 31 out to push the pot 25 out.

When the hole 50c reaches the hole 60 in disc 47 air is cut off from the groove 58 and air passes out through an outlet 60' to the inlet 40 at the upper end of jack 39, the ram thereby being lowered. Immediately afterward, when the hole 50a reaches the groove 56, air again enters the pipe 41 to raise the ram.

When the hole 50c reaches the hole 61, air passes out through the outlet 53c, in disk 47 to the pipe 30' of the jack 30.

When the hole 50b passes the end of the groove 58 air is cut off so that the cylinder 21 descends by gravity.

As shown by Figs. 7 to 10, when the hole 50c registers with the hole 59, a hole 51d (Fig. 10) registers with the hole 61 of the disk 47. When the hole 50c registers with the hole 60, the hole 51h registers with the groove 56 in the disk 47. When the hole 50a first registers with the groove 56, the hole 51c registers with the hole 60 in disk 47, and when the hole 50c registers with the hole 61, the hole 51b registers with the hole 59 in the disk 47, so that the sequence of events occurs as explained. It is to be understood that the holes 51a—51h are the holes through which the compressed air is vented after being used for operating the several jacks.

What is claimed is:

1. A device for pressing oil from seed which comprises an upper container having open ends and a lower container having open ends and perforated sides, a press head constantly in engagement with the interior of said upper container and adapted to contact seed in said upper container, means for moving said containers vertically, means for moving said lower container laterally, means for removing the pressed residue from the lower container, and means for returning said lower container to the compressing position.

2. The device of claim 1 in which said press head has seed feed means therein.

3. The device of claim 1 in which rotary means are provided to feed seed to said containers intermittently.

4. The device of claim 1 in which said upper container is aligned with said lower container and is movable into and out of contact therewith.

5. The device of claim 1 in which said upper container is aligned with said lower container, both of said containers being circular in cross-section, and said press head being circular.

6. The device of claim 1 in which said upper container is aligned with said lower container, and means are provided to bring said containers into contact with each other intermittently.

7. The device of claim 1 in which said upper container is aligned with said lower container, and means are provided to bring said containers into contact with each other when seed is being fed to said lower container.

8. A seed oil press comprising upper and lower seed containers, a vertical jack engaging said upper container, horizontal and vertical jacks engaging said lower container, a fixed press head, a ram and a ram jack adjacent said containers, said jacks being fluid operable, a control valve for operating said jacks, said valve comprising a fixed central plate, conduits connecting passages within said central plate to said jacks, a pair of perforated plates rotatable together in contact with opposite faces of said central plate, and driving means for said rotatable plates, said valve having a fluid inlet at one side of said central plate and a fluid outlet at the opposite side thereof.

9. A seed oil press comprising upper and lower seed containers, a vertical jack engaging said upper container, horizontal and vertical jacks engaging said lower container, a fixed press head, a feed gate in said press head, a feed jack engaging said gate, a ram and a ram jack adjacent said containers, said jacks being fluid operable, a control valve for operating said jacks, said valve comprising a fixed central plate, conduits connecting passages within said central plate to said jacks, a pair of perforated plates rotatable together in contact with opposite faces of said central plate, and driving means for said rotatable plates, said valve having a fluid inlet at one side of said central plate and a fluid outlet at the opposite side thereof.

10. The device of claim 8 in which the perforations in said rotatable plates are arranged to operate said jacks in predetermined order.

11. The device of claim 9 in which the perforations in said rotatable plates and the passages in said fixed plate are so arranged that when the plates are rotated, fluid pressure is sequentially applied to and released from said jacks to fill the containers, close the feed gate, press the seeds, raise the upper container, push the lower container out, depress the ram, raise the ram, return the lower container, and lower the upper container.

12. A seed oil press comprising upper and lower seed containers, a vertical jack engaging said upper container, horizontal and vertical jacks engaging said lower container, a fixed press head, a ram and a ram jack adjacent said containers, said jacks being fluid operable, a control valve for operating said jacks, said valve comprising a fixed central plate having a rotatable shaft centrally disposed therein, a pair of perforated plates mounted on said rotatable shaft which are rotatable together in a synchronized fashion in sliding contact with opposite faces of said central plate, said central plate having passages therein capable of being aligned with perforations in said perforated plates, such alignment effecting the completion of circuits for the operation of said jacks by means of fluid pressure, said valve having a fluid inlet at one side of said central plate and a fluid outlet at the opposite side thereof, and driving means for said rotatable shaft and plates, the operation of said jacks being rendered automatic by the rotation of said perforated plates at a predetermined speed, said rotation causing the completion and breaking of circuits for fluid pressure transmission and release in a sequential manner.

WILLIAM HISE.
